UNITED STATES PATENT OFFICE.

ERIC A. BLACK, OF ORANGE, NEW JERSEY.

WARP AND JACK THREAD-BREAK-STOPPING DEVICE.

Application filed November 26, 1921. Serial No. 517,896.

To all whom it may concern:

Be it known that I, ERIC A. BLACK, residing at 232 Central Ave., Orange, in the county of Orange and State of New Jersey, have invented certain new and useful Improvements in Warp and Jack Thread-Break-Stopping Devices, of which the following is a specification.

The present invention relates to all operations in knitting or weaving machines whereby a plurality of threads, called the "warp," is run from a spool frame, called the "jack" through perforated guide plates, commonly named "brasses" onto a winding drum, which forms the main part of a device, called the "warp mill."

In these operations it often happens that one or more of the threads will break during the "running-on" of the warp which necessitates constant vigilance on the part of the operator, the "warper." In such case he must stop the operation in good time, mend the broken thread and start the machine again, or, as it is often not feasible any more to connect the broken thread to the lost end, he must be satisfied with making a "mark" on the newly attached thread and leave the mending to the "weaver," who later on "beams off" the warp, that is, unwinds it again onto beams suitable to enter the weaving or knitting machine.

A break will also sometimes escape the attention of the warper and later on cause a waste of labor and time consumed in "going back" to mend or mark. Moreover, as the warp mill and the jack of the customary construction cannot be stopped suddenly without causing the threads to run together and entangle with each other or the spools themselves, a break will not seldom result in a "smash," that is, the breaking of several other threads, thereby wasting time, labor and material as well.

There have been some attempts made, especially in electrically driven looms, to provide automatic and instantaneous emergency stop and brakes, based on the principle that perforated weights, supported in normal position by unbroken warp-threads will in case of a break of their respective threads drop and form an electrical contact between

two bars or terminals, ordinarily unconnected, closing thereby an electric circuit, which in turn may energize a solenoid and thereby actuate a cut-out switch and a brake 55 bringing the loom to a stop.

These electric contact devices however, though apparently very sensitive, often fail and refuse to work in practice, and for the very reason of their sensitiveness. A good 60 electrical contact is only possible between clean surfaces, and if, as is inevitable in the operation of textile machinery, the air is saturated with fine dust particles, this non-conductive dust or even coarser fluff and lint 65 will in time cover the terminal bars and thereby materially interfere with good electrical engagement. In addition thereto the jarring of looms or warp mills will often dislocate the fallen weight again and break 70 the disengaging circuit, after it was momentarily closed.

These electrical contact devices have therefore proved rather unreliable in action.

The leading object of this invention is to 75 provide a thread-break stopping mechanism, which, while being as sensitive as these electrical devices will at the same time be absolutely positive and unfailing in its action.

A second and more particular object is to 80 substitute reliable mechanical means for the more or less uncertain contact feature of the electrical devices, while retaining and utilizing the convenience and quick action of the electrical current.

A third object is to devise a stopping mechanism which will not materially interfere with the smooth unwinding or rewinding 85 of the threads.

A fourth object is to provide a brake 90 mechanism which, when the motive impulse of the warp drum is interrupted, will instantaneously bring the revolving drum to a standstill.

A fifth object is the provision of means 95 to prevent the occurrence of a "smash," namely of means to simultaneously put a brake to all spools on the jack and thereby to bring the whole warp to a quiet rest without undue slack or tension.

A sixth object is the arrangement of parts 100 in such a way that the starting again of the

warp mill is simplified and will succeed the interruptions, caused by the breaking and mending of the threads, without much manipulation or further loss of time.

5 A seventh object is to provide means for putting all threads, running through the brasses, under the control of the stopping device in an easy time- and labor-saving manner.

10 These various objects are attained by the novel mechanism and combination of parts, described hereafter and shown in the accompanying drawings, forming a material part of this disclosure, and in which:—

15 Figure 1 is an assembled side view showing the warp mill, the motor drive for the same and the application of the described invention to these parts.

20 Figure 2 is a plan of these same installations, a part of the warp mill being broken away to reveal the brake mechanism underneath it.

25 Figure 3 is a continuation of the side view shown in Figure 1, illustrating a jack or spool frame provided with the novel means to put a simultaneous brake to all its spools and partly forming the object of this specification.

30 Figure 4 is a top view of the jack frame with the greater number of spools removed and a part of the creel shown broken away, to better disclose the operative members of the jack brake.

35 Figure 5 is a detail view of the drum brake showing the spindle of the thread-break stopping device and the pillow blocks in which the brake fork is journaled in section.

40 Figure 6 is an enlarged detail of the threaded end of the drive spindle, illustrating the drop weight funnel and the pitted drum rotating underneath it.

Figure 7 is an end view of these parts, the drive spindle being shown in section.

45 Figure 8 is an enlarged sectional view of the threads running through the brasses, and the drop weights suspended above the funnel shown in Figure 6.

Figure 9 is a partial front view of these brasses looking towards the jack.

50 Figure 10 illustrates the jack or creel-brake stops more fully in detail.

Figure 11 is a partial front view of the parts shown in Figure 10 with the spool and its spindle omitted.

55 Referring to the drawings, the numeral 15 designates the warp drum, either keyed on or otherwise fixedly supported by the shaft 16, which rotates in the pillow blocks 17^a and 17^b. In this instance the shaft 16, apart from one of its extreme ends 28, and the core in the warp drum are of square section (see 18) and form therefore a fixed combination.

60 The square shaft 16 is provided with two sleeves 29^a and 29^b, with square cores and

cylindrical mantles to run in the pillow blocks 17^a and 17^b respectively. The extreme end 28 of the shaft 16 is upset to the same diameter as the sleeve 29^b, and both the shaft end 28 and the extreme end 29^c of the sleeve 29^b are threaded the same way and in the same sense to receive the hexagonal nut 30 which couples the sleeve 29^b and the shaft end 28 together. These features and appurtenances of the drum shaft 16 are however not indispensable and form no subject for any claim in this specification.

65 On the sleeve 29^b, where it protrudes from the pillow block 17^b, is also keyed or otherwise fixedly supported a wheel 19, connected by a chain or belt transmission 20 with the driving wheel 21, fixed on the counter shaft 22. This countershaft may be supported or journaled in any convenient manner, as circumstances may determine it, in hangers, or, as shown here, in pedestals 23 and 24. On the countershaft 22 is mounted the spur gear 25 which together with the pinion 26 forms the gear transmission that connects the warp mill with the electric motor 27, which supplies the driving power to the warp drum, and on whose shaft 27^a the pinion 26 is fixedly mounted.

70 The threads 40 (see Figures 1 and 3) are coming from spools 44, running on spindles 45, mounted on horizontal creel beams 46 of a spool frame, a so called "jack". This spool frame consists of a pair of stepped cheeks or sideboards 41, forming a terraced stand for the creel beams 46. The sideboards 41 on their part are mounted and supported by two pairs of upright columns 42^a and 42^b, resting on a base 43.

75 From the spools 44 the threads are run through a set of common brasses 47 (Figure 1) onto the warp drum 15.

80 So far the description has had to deal with minor and more or less customary parts of a warp mill device, on which no claim for novelty is made by the inventor. The following described details however form, properly speaking, in their combination and arrangement the subject matter of the disclosed invention.

85 Numeral 50 designates a shaft, running at right angle to the drum shaft 16, underneath the warp drum. In front of the warp drum this shaft is loosely jacketed by a bushing or sleeve 51, so that it can be moved freely in an axial direction through the same. The latter however, while being journaled in the upper part of the pedestal 24, and crossing at right angles the countershaft 22, is confined lengthwise by the collar 52, fastened on it by the set screw 53 on one end of the pedestal bearing 60, and by the axially stationary half 54^a of a jaw clutch, fastened on it by the set screw 55 on the other end of the pedestal bearing. The pedestal 24

therefore is provided with bearings for the shaft 22 as well as for the sleeve 51.

The latter bearing 60 furthermore is split forklike into halves, 60^a and 60^b, to guide between them the spiral gear 61, which is mounted on a key, indicated by the short dotted line 61^a (Figure 1) and let into a key-way cut into the sleeve 51.

The other half of the jaw clutch, designated by numeral 54^b, is fastened by key 54^c and set screw 54^d to the shaft 50, so that it will engage or disengage with the axially stationary half 54^a, as the shaft may move in one or the other direction respectively.

15 The spiral gear 61 engages another spiral gear 62, fixedly mounted on the counter-shaft 22, and receives its impulse from this motor driven shaft. The spirals of course must be cut in the proper sense, so as to 20 eventually rotate the shaft 50 in the required peripheral direction, as indicated by the arrow 56.

On the shaft 50 is also mounted a hand wheel 63 by a set screw 63^a and key 63^b for 25 throwing in the jaw clutch by means described hereafter. The end of the shaft is provided with a collar 65, fastened onto or integral with this shaft and shaped with an annular groove on its circumference 30 around which the clamp 66 loosely fits, said clamp consisting of two semi-circular halves, bolted together with their outwardly flanged ends 66^a and 66^b and sandwiching between these ends the tips of a fork-like device 35 67, consisting of a pair of bars, twisted and coupled together in the manner illustrated.

In alignment with the axis of shaft 50 these bars, properly bent and rebent, form 40 a guide slot 68, embracing the handle 69 of an electric knife switch, fulcrumed at 70 and adapted to engage the motor switch 71^a or the cut-out switch 71^b, according as it is thrown one way or the other. When pushed by hand into switch 71^a it starts 45 the motor 27, circuit connections being established in any well known manner, as indicated by the dash lines in Figure 1 which are continued in Figure 3, the positive terminal being designated by numeral 50 72, the negative by 73.

When however the shaft 50, travelling backwards from the warp drum, disengages the jaw clutch, it simultaneously throws the handle 69 out of contact with switch 71^a, 55 and the impetus of the thrust as well as its own weight throws the handle into engagement with the cut-out switch 71^b. The arrangement and function of the switch and its accessories will be explained later.

60 At a suitable point underneath the warp drum is provided on the shaft 50 furthermore a collar 80, adjustably mounted on a key 81 (see Figure 5). This collar is formed similar to collar 65 and is provided 65 with similar accessories, namely two semi-

circular clamps 82^a and 82^b, bolted together, as shown in Figure 5, but instead of the fork-like attachment they have two pintles 83^a and 83^b, located half way between the bolt couplings and diagonally to the shaft 70 axis.

Underneath the collar 80 are arranged two floor stands or pillow blocks 84^a and 84^b, in which is journalled the shaft 85, confined in axial position by the cotter pins 86^a and 86^b. On this shaft is fulcrumed a fork-like device, consisting of the two one-armed levers 87^a and 87^b. Their upper tips are provided with slots (see 88 Figure 1) which embrace the pintles 83^a and 83^b, while about 80 half-way on their length they are shaped to form two journals 89^a and 89^b for the shaft 90, secured therein by the upset head 91 and the set screw 92. This shaft is extended sideways, and on its reduced end 93 85 is fastened and held in place by a cotter pin 94 the free end of a band brake 95, which, as shown in Figure 2, surrounds a flanged brake wheel 96, keyed on the drum shaft 16, and with its other stationary end 90 is attached in any convenient way to the frame structure, for instance to a bolt or bracket 97^a, protruding from the support 97 of the pillow block 17^b.

The extreme end of shaft 50 is provided 95 for some distance with a square thread 100 of rather steep pitch (Figures 1, 2 and 6) fitting into the hub 102 of the wheel 101. This wheel runs in ball bearings, mounted in a pedestal 103^a, 103^b, which, if viewed 100 at right angles to the shaft, resembles a reversed U and is split in the middle, normally to the shaft, to insert the wheel 101 into its journals 104^a and 104^b. Around the extending parts of the hub 102 and 105 into the rim of the journal are cut ball races 105^a and 105^b, furnished with the necessary number of balls which are held in place by the annular flanges 106^a and 106^b, bolted on the pedestal part 103^a and 103^b. 110

After assembling the wheel and the ball bearing parts the split halves are bolted together by bolts 107 and held in place by the foundation bolts 108. The halves 103^a and 103^b can be extended on the descending 115 side of the wheel 101 to form two halves of a flat tray or pan 109 for a purpose explained below.

Where the two halves of the pedestal meet on the top, they leave a circular opening for 120 the insertion of a small funnel 110. This funnel reaches with its lower cylindrical part 110^a almost down to the periphery of wheel 101. It is on its outside provided with two pintles or dowel pins placed opposite to each other, 110^b and 110^c, to which correspond two slots 111^b and 111^c, extending from the periphery of the circular opening in the pedestal through which funnel 110 is inserted. It will be evident that, 125 130

4
after the funnel is inserted in such a manner that the pintles pass through these slots, and the funnel is turned for ninety degrees around its axis, it is then secured against 5 upward dislocation and removal.

It is also understood that the same object could be obtained in various other ways, for instance by the projection of a pin or a set-screw from the pedestal into the neck of the 10 funnel or the like.

Into the mouth of the funnel 110 fits the neck of a much larger funnel 112, whose mouth may have any size required for the object explained hereafter, in this instance 15 being shown in the shape of a narrow oblong 112^a (Fig. 2).

Immediately above this funnel is suspended in any suitable way a set of special brasses 113, 114, and 115, shown in Figure 1 20 and more explicitly in Figure 8. These brasses are rhombic plates, provided with perforations, arranged in rows, parallel to the sides, so that they straddle each other in a vertical projection.

25 The holes in each plate register with the corresponding holes in the other two plates. The holes 113^a and 115^a in the two outer plates need only be large enough to guide the warp threads without friction or tension. 30 The first plate 113 is lined furthermore with annular bosses 113^b through which the holes are drilled concentrically. These bosses fit loosely into the holes 114^a of plate 114, and their minimum height above the plate 113 35 corresponds to the thickness of plate 114.

On each warp thread passing through the three consecutive holes is placed a rider in the form of a drop weight 116. These are spherical bodies perforated diametrically 40 with slightly flattened surfaces 116^a and chamfered rims 116^b where the perforations reach the surface. The width of the little spheres between the flattened ends is equal to the thickness of plate 114, and their 45 spherical diameter equals the diameter of the bosses 113^b.

On the circumference of wheel 101 is arranged at equal distances a plurality of 50 nearly hemispherical pits 118, the spherical center lying just a little below the periphery of the drum in a radial direction towards the drum center, so that a drop weight 116, placed into one of these pits, has a trifle less than half of its volume protruding from the 55 drum mantle.

The operation of the device, as far as described, is as follows:

The brasses 114 and 115, being removed 60 from their supporting pegs 117, are put upon each other, plate 114 being uppermost; then the drop weights 116 are placed into the openings 114^a and flattened down so that their surfaces are flush with the upper surface of plate 114, and their perforations 65 register with those of plate 115. Then this

combination is replaced upon the pegs 117, in contact with plate 113, the holes, weights and bosses 113^b being in close registration. Thereafter the warp threads, coming from the jack, shown in Figure 3, are drawn with 70 hooks through the brasses 113, 114, 115, and the ordinary brasses 47, which are used for making a "tie," in case of removing the warp from the drum.

If now the bosses on brass 113 are pressed 75 through the openings in brass 114, it will be seen that the weights riding on the warp threads are pushed out of them, separating the plates 114 and 115 at the same time, as shown in Figure 8. The weights are therefore hung in such a position, that when a thread breaks, its corresponding weight will tumble down between the other threads through the funnel 112 into the bottom of funnel 110. Here it will settle in the next 80 oncoming pit 118 of the revolving wheel 101, assuming of course, that the machine is in operation, the knife switch 69 and the clutch 85 54 being thrown into engagement.

This wheel 101, though not fastened on the screw end 100, has been kept so far in rotation by it, as it is confined in an axial direction, and the friction of the thread against the hub is far greater than the almost negligible friction in the ball races 115^a 85 and 115^b. Now however the drop weight imbedded in one of the pits 118, forms a stop, as it cannot pass through the narrow clearance between the circumference of the wheel 101 and the bottom of the fixed funnel 110. The wheel therefore is brought to a sudden 90 halt, and the screw end, continuing its rotation, begins to back out of the hub.

Consequently the whole shaft 50 starts to travel axially backwards from the pedestal, 105 simultaneously disengaging the clutch, throwing the knife switch out, disconnecting thereby the motor drive and—by pulling the collar 80 backwards—actuates the band switch 95.

To set the machine in motion again, after the broken thread is tied or otherwise has been taken care of, the small funnel 110 is turned half way around so that the pintles 110^b will pass through the slots 111^b and 111^c 115 and the funnel can be lifted enough to let the ball 116 pass.

If now the knife switch is thrown in again and the clutch is reengaged, the wheel 101 begins to rotate again, and the weight, going along with it on the periphery, drops finally into the tray 109, to be picked up and reused again.

It remains to be described, what provisions are made to prevent "a smash", that 125 is, to stop all spools on the jack simultaneously.

In addition to the ordinary parts of a jack frame mentioned already, the invention provides a movable rack or carriage, under- 130

neath and parallel to the creel frame, consisting of two side beams 120 with stepped tops, similar to the stationary side boards 41 of the jack. The steps 121 correspond to 5 the number and position of the creel beams 46, though offset somewhat towards the rear of the frame. To each step is fastened a tie beam or purlin 122, connecting the side beams 120.

10 In addition these side beams are rigidly braced by the bottom beams 123^a and 123^b, and under them are provided four roller casters 124, running on rails 125. The section of these rails and those of the rollers 15 124^a must be such that they guide each other and prevent derailing, that is a flange 126 must be provided on the outside or inside of either the rollers or the rails. The rails are turned upwards at their ends 127, so as 20 to limit the travel of the rollers to but a short distance. The rails must be mounted rigidly to the main jack frame in a suitable way, for example by being attached to two rail sills 128, extended between two headers 25 129^a and 129^b, which in turn are framed into the main structure of the jack.

Through the purlins or tie beams 122 are horizontal holes drilled, in the direction in which the carriage is movable, each hole corresponding to and placed underneath a spindle on the upper creel beam, and through each of these holes is drawn one end of a pliable looped wire 130, as shown in Figure 30 10. These wires are bent to form a circular loop 130^a to make them resilient, and the end passing through the purlin 122 is threaded to receive a nut 130^b which, when tightened, secures the position of the wire in the purlin.

Behind each spindle 45 is a small hole 131 40 drilled, vertically through the creel beams 46, through which can loosely pass a pin 132, provided with an eye 132^a, which is slipped over the free end of the wire 130. It is evident from the detail, shown in Fig. 45 10, that this construction represents an easily adjustable arrangement, as a slight change in the bend of wire 130 tends to alter the position of the push bar 132, thereby the point of contact between the latter and the 50 bobbin and consequently the moment of braking action.

On the rear end of the carriage is fastened with brackets 133 one or more solenoid cores 134 of soft iron, which extend partly into 55 corresponding central apertures on one or more powerful solenoids 135, supported by brackets 136.

These solenoids are energized by an electric current which can be shunted off the 60 main duct in the usual way, as shown by the shunt wire, switching off the negative terminal at 140 (Figure 3) through the solenoid to 141, from there to 142, from 142 (Figure 1) to 143 at the cut out switch, 65 thence through the knife, shown dotted, to

144, thereafter to 145, and from 145 (Figure 3) to the positive terminal.

The operation of this brake device is as follows:

When the knife switch 69 is thrown out 70 by the forward thrust of the shaft 50, it falls back and engages with the switch blades shown at 71^b. Thereby, as explained above, an electric current is closed, energizing the solenoids 135 which in turn magnetically attract the soft iron cores 134 and thereby pull the carriage upwards. This movement brings all the little looped wires 130 into play, which simultaneously push all the pins 132 up through their guide holes 131, and 80 these pins, striking against the still rotating spools, arrest them and bring them to an instantaneous stop.

On setting the machine in motion again 85 the knife 69 is disengaged from the switch blades at 71^b, the shunt current is broken, the solenoids de-energized, and the carriage dropped back into its lower position, pulling down the wires and pins with it and releasing thereby the spools to rotate freely. 90

Thus it will be seen, that all the different objects of this invention, as formerly stated, are attained in a simple efficient manner and are realized in this labor-and-time-saving emergency-stop for warps and jacks. 95

Other forms and modifications are possible along the lines indicated, and it is therefore understood that the invention is not to be confined to the exact description and showing presented but rather to the claims 100 appended hereto.

I claim:

1. A drum, upon which a thread is being wound, a mechanism to actuate said drum, a perforated ball, normally suspended by 105 the upwinding thread, means whereby this ball, when released by the breaking of said thread, is directed during its free fall in such manner, that it ultimately lodges as a wedge between two operating parts of said mechanism, acting thereby as a frictional stop to these parts, and means to transmit this stopping action onto the drum-actuating parts of said mechanism. 110

2. A drum onto which a thread is being wound, a brake to stop said drum, mechanisms to actuate said drum and said brake, a wheel, means to rotate said wheel, a stationary member in close but not touching proximity to the wheel, a perforated ball, 120 normally suspended by the upwinding thread in such position that when the thread breaks, the ball is disconnected so as to act as a free falling body, means to direct the fall of this body in such manner that it is 125 ultimately wedged between the stationary member and said rotating wheel, acting thereby as a brake-stop upon the wheel, and means connected with the wheel, to transmit this stopping action directly onto the 130

mechanisms which actuate the drum and the brake.

3. A thread-break stopping apparatus, comprising a thread-winding drum, an electric motor to actuate said drum, a brake to stop said drum, a switch to direct and divert electric current to and from the motor, a rotating cylinder, operated by the motor, a perforated ball, normally suspended by the thread alone, which winds onto the drum, means, whereby, when the thread breaks and the ball is released, the latter is wedged at the end of its fall against the periphery of said rotating cylinder, acting as a brake-stop upon it, and means, connected with this cylinder, whereby the switch, when said cylinder stops rotating, is changed from a motor feeding to a stopping position, substantially as shown.

20 4. The combination with a thread-winding drum, an electric motor to operate said drum and a cut-out switch to start and stop the motor; of a drop weight, normally suspended by the thread winding onto the drum, a vertically rotating wheel, having a depression on its peripheral surface, into which said drop weight would fit with part of its bulk protruding beyond the periphery, a casing, supporting the rotating wheel, a bottomless receptacle for the drop weight, attached to the top of the casing in such a position, that when the thread breaks and the weight, released from its suspended position, falls into the bottomless receptacle and, through it, reaches the depression on the periphery of the wheel, it will be wedged in a clearance between the receptacle and the periphery of said wheel, acting as a brake stop to the latter, a shaft, provided with a helix, threaded through said wheel in such manner that, when the shaft turns, it normally rotates the wheel by friction, and when the latter is forcibly stopped, the shaft is moved in an axial direction, means to drive this shaft from the motor and means to transmit any axial movement of the shaft onto the cut-out switch, controlling the motor, for the purpose of throwing out this switch and stopping the motor and thereby the winding drum, substantially as described.

5. The combination with a warp and jack thread-break stopping apparatus, comprising substantially a bobbin frame, a warp drum, a mechanism to drive the warp drum, a plurality of drop weights, normally suspended by the warp threads, and adapted to stop by the fall of one of them the mechanism, driving the drum, a plate, having a plurality of holes to guide the warp threads on their way from the bobbin frame to the drum, and a support for this guide plate; of two other thread-guiding plates, movably held by said supports in parallel juxtaposition to the first-mentioned guide plate, and pro-

vided with thread-guiding holes, registering with the holes in the first plate, the holes in the new plate next to the first one being large enough to serve as cells for the suspended drop weights, and the third outer plate being provided with bosses, concentric to its thread-guiding holes, fitting into the holes of the middle plate and adapted therefor to dislocate the drop weights from these holes simultaneously towards the first-mentioned guide-plate, when the other two plates are brought into contact, substantially as shown, and for the purpose of placing the drop weights into a tripping position, if their respective threads should break.

6. The combination with a thread-break stopping apparatus, comprising substantially a thread-winding drum, an electric motor to drive the drum, a knife switch to start and stop the motor, a drop weight, suspended by the thread, winding onto the drum, and adapted to be used as a friction stop; of a shaft, horizontally mounted underneath the drum and slidable in an axial direction, one end of the shaft being provided with a helix, means to rotate said shaft independently from its axial movement, a drive, connecting the rotating means with the electric motor, a wheel, pitted on the circumference with a plurality of depressions, adapted to catch the falling drop weight, the hub of the wheel being threaded and slidably mounted on the helix of the shaft, means to arrest the wheel by friction in its joint movement with the rotating shaft, when it contains the fallen drop weight, thereby forcing the rotating shaft to travel axially outwards, in conformity with the friction of its helix within the threaded hub of the wheel, and a non-rotatable member, on the other end of the shaft, mounted in alignment and universally jointed with it, said member being adapted to push the knife switch out of contact, when axially moved, jointly with the rotating shaft, substantially as described and for the purposes shown.

7. The combination with a thread-break stopping apparatus, comprising substantially a thread-winding device, an electric motor to actuate the device, a shaft, horizontally mounted, movable in an axial direction and being formed to act as a pushing and pulling bar, a drop weight, normally suspended by the thread, which winds onto the drum, a mechanism, being adapted to move said shaft, when said mechanism is acted upon by the fallen drop weight, in case the suspending thread breaks; of a knife switch, comprising a one-armed vertical tilting lever, fulcrumed at the lower end, and two electric cut-outs, located oppositely to each other in the swinging plane of the switch lever in such a way, that the lever, forming the knife switch, may engage

with either one of them; an electric brake, acting upon the winding device, means to connect the electric brake current with one of the said cut-outs, means to connect the 5 motor current with the other cut-out, and means to bring the shaft, formed to act as a pushing and pulling bar, in operative engagement with said switch lever, so that, by pushing it in one direction or pulling it in 10 the other direction, it will respectively cause the current for the motor or that for the brake to be connected or disconnected.

8. In a warp and jack stopping mechanism, the combination with a warp-winding 15 drum, means to impel said drum, and means to stop it; of a bobbin frame, comprising substantially a base frame, a plurality of parallel stationary bobbin shelves, mounted on the base frame, a plurality of vertical 20 bobbin spindles, fastened on these shelves, a travelling frame, forming a rack, corresponding to the extent and registering with the arrangement of these bobbin shelves, said travelling frame being movable for a limited 25 distance in two opposite directions, parallel to the plane of the bobbin shelves, and guidably supported by the base frame underneath said shelves, a plurality of elements, guidably arranged aside the spindles in the 30 bobbin shelves in such a manner, that each element, when moving in one direction, would strike against and frictionally arrest one of the bobbin reels, should the same be mounted on the respective spindle, and, 35 when moving in the opposite direction would release said bobbin reel again, means to engage and actuate all these elements simultaneously from the travelling frame, and means connected with the drum-stopping 40 means, mentioned above, to move the travelling frame in either direction for the purpose of actuating the above said elements, thus braking or releasing the bobbins simultaneously.

45 9. In a warp and jack stopping mechanism, the combination with a warp-winding drum, a motor to impel the drum, and means to interrupt the motor current and stop the winding drum; of a bobbin frame 50 comprising substantially a base frame, a plurality of parallel stationary bobbin shelves, mounted on the base frame, a plurality of vertical bobbin spindles, fastened on these shelves, a travelling frame, forming a rack, corresponding to the extent and registering with the arrangement of these bobbin shelves, said travelling frame being movable for a limited distance in two opposite directions, parallel to the plane of the 55 bobbin shelves, and guidably supported by the base frame underneath said shelves, a plurality of elements, guidably arranged aside the spindles in the bobbin shelves in such a manner, that each element, when 60 moving in one direction, would strike

against and frictionally arrest one of the bobbin reels, should the same be mounted on the respective spindle, and, when moving in the opposite direction would release said bobbin reel again, means to engage and actuate 50 all these elements simultaneously from the travelling frame, a solenoid, a support for the solenoid, an iron plunger, attached to the travelling frame, and formed to serve as a magnetic core to the solenoid, the 55 plunger and the solenoid being so arranged, that when the solenoid is energized and the plunger magnetically attracted, the latter pulls the travelling frame towards the solenoid, means to energize the solenoid, so when the motor current is interrupted and thus to simultaneously operate the elements, acting as bobbin brakes, and means to pull the travelling frame back into a brake-releasing position, when the solenoid is de- 65 energized.

10. In a warp and jack thread-break stopping mechanism the combination with a warp drum, a bobbin frame, comprising a plurality of bobbin spindles, means to impel 90 the warp drum and automatic means to stop it, in case that one of the warp threads breaks; of a plurality of push rods, guidably arranged aside the spindles on the bobbin frame in such manner, that each rod is 95 adapted to strike against and frictionally arrest a bobbin reel, should the same be mounted rotatably on the respective bobbin spindle, a plurality of adjustable and pliable elements, engaging with said push rods, 100 and means, connected with the drum stopping means, to actuate all said elements contemporaneously for the purpose of braking the bobbin reels or releasing them again, substantially as described. 105

11. In a warp and jack stopping mechanism, the combination with a warp drum, a bobbin frame, an electric motor to impel the warp drum, and a cut-out switch to start and to stop the motor; of an automatic electrical switch device, comprising a plurality of push rods, slidably supported on the bobbin frame in such manner, that each rod is adapted to strike against the bobbins on the bobbin frame in an axial direction, exerting 110 thereby a braking action, a plurality of adjustable resilient elements, engaging with said push rods, a movable support, on which said elements are mounted, and electromagnetic means to impart a reciprocating 115 motion to said support, transmitting such motion to the push rods by means of said resilient elements. 120

12. In a warp and jack stopping mechanism, the combination with a warp drum, a 125 bobbin frame, supporting a plurality of axially upright bobbins, means to impel the warp drum and means to stop it; of an emergency brake, consisting of a plurality of separately adjustable, cooperating push-rods, 130

adapted to stop all bobbins on said frame by lifting them simultaneously in an axial direction for the purpose of frictionally stopping them, imparting an equal tension to all the warp threads and preventing the entangling of the same.

In testimony whereof, I have signed my

name to this specification in the presence of two subscribing witnesses, this 18th day of October, 1921.

ERIC A. BLACK.
